UNITED STATES PATENT OFFICE.

THOMAS F. HANDLY, OF ALLEGHENY, PENNSYLVANIA.

PENCIL, PENHOLDER, AND LIKE ARTICLE.

No. 897,530.

Specification of Letters Patent.

Patented Sept. 1, 1908.

Application filed June 13, 1906. Serial No. 321,528.

To all whom it may concern:

Be it known that I, THOMAS F. HANDLY, a citizen of the United States of America, residing at Allegheny, in the county of Allegheny and State of Pennsylvania, have invented certain new and useful Improvements in Pencils, Penholders, and Like Articles, of which the following is a specification, reference being had therein to the accompanying drawing.

This invention relates to pencils, penholders, and like articles, and its object is to provide means for deterring the users of pencils from placing them in the mouth or against the tongue.

The danger of transmitting a disease from one person to another through the habit of wetting the point of a pencil by placing it in the mouth, is well known, and the present invention aims to avoid this danger, and to prevent the contracting of the habit, particularly by children, of placing pencils in the mouth.

My invention consists in providing, as a new article of manufacture, a pencil or like instrument having a face secured thereto, said face completing the normal configuration of the instrument and being a deterrent.

My invention further consists in the improved construction hereinafter fully described, illustrated in the accompanying drawings, and particularly pointed out in the appended claims.

In the drawings, in which similar reference characters indicate similar parts in each of the views: Figure 1 is a side elevation of a lead pencil embodying my invention, the view showing one of the sides of a polygonally-sided pencil provided with a deterrent face, Fig. 2 is a transverse sectional view of the same, Fig. 3 is a side elevation of a modified form, the view showing the deterrent face as of less width than the width of one of the sides of the pencil. Fig. 4 is a transverse sectional view of the construction shown in Fig. 3, Fig. 5 is a perspective view showing a pen-holder having a deterrent face applied longitudinally thereof.

1 designates a pencil of polygonal form in cross section, having one of its sides provided with a face or facing portion 2^a formed of a deterrent substance of a harmless nature. I preferably employ a compound made from bitter herbs and water, but any harmless substance, compound or mixture having a

bitter, acrid, or otherwise offensive taste, 55 may be employed in forming the face 2^a. The face or facing portion may be secured to the pencil in any suitable manner, as by providing a groove 3 on one of the sides of the pencil or, as shown in Fig. 5 along the exposed surface of a pen-holder which is circular in cross section, within which groove the deterrent is placed, said deterrent having its exposed surface substantially in the normal plane of the surface of the pencil, thereby 65 completing the normal configuration of the pencil. Or, the face 2^a may be provided by making one of the sides of the pencil of a sufficiently greater width to cause the face or facing portion, when applied to such side, 70 complete the normal configuration of the pencil, the face, in such latter case, having an exposed surface extending on adjacent sides of the pencil. The face in Figs. 3 and 4 is designated as 2^b, and in Fig. 5 as 2^c. The 75 word "face" as used herein, is intended to apply to the deterrent portion as contradistinguished from the sides or other surface of the pencil or other implement which may be used. And in this respect it is to be understood that the term "face" will apply to the exposed deterrent whether the exposed portion is of the form shown in Figs. 1 and 2 or of the form shown in Figs. 3, 4 and 5, that is to say, whether or not the exposed surface is 80 equal to or less than the width of any side of a polygonal pencil or less than the exposed surface of the pencil which is round in cross section, the term indicating an exposed surface of a material which is different from the 85 material of the pencil casing or pen-holder, and by reason of such distinguishing characteristic providing on the pencil a complete exposed surface or face of the deterrent material.

In each of the forms shown, a sharpening of the pencil will not affect the presence of a portion which will act to deter the placing of the pencil within the mouth of the user.

While I have shown and described several 100 forms in which the pencil or other instrument may be provided with a deterrent which is exposed substantially on the plane of the surface of the pencil, it will be understood that I have not pointed out all the ways in which 105 such structure may be provided, and I reserve the right to make any and all such modifications thereof as may fall within the

spirit and scope of the invention, as expressed in the accompanying claims.

Having thus described my invention what I claim as new, is:

- 5 1. As a new article of manufacture a pencil or like instrument having a face secured thereto, said face completing the normal configuration of the instrument and being a deterrent.
- 10 2. As a new article of manufacture, a pencil or like instrument having a face secured thereto, said face completing the normal configuration of the instrument and being a de-

terrent, said face extending and being exposed throughout the length of the instrument.

3. A pencil, pen-holder or like article formed with an external longitudinal groove containing a deterrent substance or compound.

In testimony whereof I affix my signature in the presence of two witnesses.

THOMAS F. HANDLY.
